UNITED STATES PATENT OFFICE.

EDWARD D. FALES, OF CHICAGO, ILLINOIS, ASSIGNOR, BY MESNE ASSIGNMENTS, TO
FIRST TRUST AND SAVINGS BANK, TRUSTEE, OF CHICAGO, ILLINOIS.

AUTOMATIC COMMON-BATTERY TELEPHONE-EXCHANGE.

1,186,563.

Specification of Letters Patent.

Patented June 13, 1916.

Application filed September 26, 1906. Serial No. 336,353.

To all whom it may concern:

Be it known that I, EDWARD D. FALES, a citizen of the United States of America, and resident of Chicago, Cook county, Illinois, have invented a certain new and useful Improvement in Automatic Common-Battery Telephone-Exchanges, of which the following is a specification.

My invention relates to automatic or semi-automatic telephone exchange systems in general, but more particularly to automatic or semi-automatic exchanges in which the switches are operated on the step-by-step principle, and especially to common battery telephone exchanges in which connectors are employed for establishing connection with called subscribers' lines.

Generally stated the object of my invention is to provide an improved and highly efficient automatic or semi-automatic telephone exchange system.

Special objects of my invention are to provide an improved construction and arrangement whereby current for talking purposes may be supplied through the connectors without the necessity of employing more than four coils or relay windings for feeding current from the common battery to the talking circuit; to provide an improved construction and arrangement whereby talking current is supplied through the front and back-bridge relays of the connectors without the necessity of employing certain devices which have heretofore been considered necessary, such, for example, as differential relays and additional coils or windings in the bridges, and whereby the two front-bridge relays and the two back-bridge relays of each connector are not only sufficient for feeding talking current to the talking circuit, but are also sufficient for connecting and releasing purposes—that is to say, sufficient for controlling the connecting and releasing operations of the connectors; to provide an improved construction and arrangement whereby, if the front-bridge or line relays are energized simultaneously while the back-bridge relays are deenergized, all switches which may have been operated are then automatically released or restored to normal condition; to provide an improved construction and arrangement whereby if the front or the back bridge relays are deenergized, after the two relay bridges are

energized, the switches are then also released or restored to normal condition; and to provide certain details and features of improvement and novel combinations tending to increase the general efficiency and improve the service of a telephone exchange system of this particular character.

To the foregoing and other useful ends, my invention consists in matters illustrated in the accompanying drawings and herein-after described and claimed.

In the accompanying drawings, Figure 1 is a diagrammatic perspective view of my improved connector. Fig. 2 is a diagrammatic view in which the circuits and apparatus involved when two subscribers are connected are illustrated. The calling subscriber is shown at A and the called subscriber at A'. At the central office the common battery B is shown, which supplies current for all switching purposes and for talking. The selector C allotted to the calling line is shown at the left connected with said line. A similar selector C' of the called line is shown to the right, and, in addition, the connector D. Fig. 3 is a similar view of a modified form of the connector D.

The substation A may be of any suitable or approved type. The one in connection with which I have elected to illustrate my invention comprises a receiver 2, a switch-hook 3 for controlling the substation circuits, which controlling operations are accomplished through the medium of any suitable means, such as the cam arms 4, 5 and 6. The said substation comprises the usual transmitter 7, induction-coil 8 having the primary winding 9 and secondary winding 10, the ringer 11, and condenser 12 in the ringer circuit. Being an automatic substation it is provided with the usual vertical and rotary impulse springs 13 and 14, and with the release-springs 15, 16 and 17. Said substation is, of course, provided with a dial, which is not shown but which is secured to the shaft 18, together with the locking dog 19. Furthermore, there is a locking cam 20 that locks the dog 19 while the receiver is on the switch-hook to prevent a rotation of the dial. The substation ground circuit is normally broken between the ground springs 21 and 22 by the cam arm 4, but when said springs are together ground is provided to the ground post 23 and to

the release spring 17, as is usually the case in telephones of this type. For operating the impulse springs 13 and 14 the substation is provided with an impulse wheel 24 that is secured to the shaft 18 which carries on its periphery the so-called vertical teeth 25 and one rotary impulse tooth 26. The said impulse teeth are so arranged that when the dial is drawn down the impulse springs 14 and 13 are not carried into contact with the ground post 23, but as the dial returns, first the vertical teeth engage the vertical impulse spring 13, and after they have completed their work the rotary impulse tooth 26 operates the rotary impulse spring 14. In this operation the subscriber's vertical line conductor 27 is first given a number of ground impulses, and then the rotary line conductor 28 is given one ground impulse. It will be noticed that as long as the dial is out of normal position the construction is such that the dog 19 permits the primary circuit springs 29 and 30 to separate, thus preventing the impulses that are delivered to either line conductor from passing to the other.

The selector C and the selector C' are identical and are disclosed in Patent No. 815,321, granted March 13, 1906, to Keith, Erickson and Erickson. In the drawings both selectors are similarly represented. The line wipers 31 and 32 and the private wiper 33, which are carried by the switch-shaft, are shown; also the side switch wipers 34, 35, 36 and 37. In normal position the said wipers, of course, engage the contact points 38, 39, 40 and 41; in second position the contacts 42, 43, 44 and 45, and in the third position the contact points 46, 47, 48 and 49. The operations of the switch, while a call is being made, are, of course, controlled by the vertical and rotary line relays 50 and 51, which in turn control the vertical magnet 52, private magnet 53, rotary magnet 54 and release magnet 55. After the side switch passes to third position the release of the selector, as is well known, is controlled through the medium of the so-called back-release relay 56. As soon as the switch is operated the switch-shaft permits the off-normal springs 57 and 58 to come into contact, whereby a guarding potential is established by way of the private normal conductor 59 to the private bank contacts of the connector, to prevent another subscriber from interfering with the line, and from establishing connection with the said line by way of the normal line conductors 60 and 61. When the off-normal spring 57, however, is in normal position it rests in engagement with the spring 62, whereby the bridge-cut-off relay 63 is retained in connection with the private normal conductor 59, so that whenever the line is called the said bridge-cut-off relay 63 is energized,

whereby the line relays 50 and 51 are disconnected from the battery and from each other.

The connector D is an improvement upon the connector disclosed in Patent No. 815,176, granted March 13, 1906, to Keith, Erickson and Erickson. The general mechanical details are very much the same, although their functions and the circuits are materially different. The usual switch-shaft 75 64 of said connector is provided with the line wipers 65 and 66 and the private wiper 67, which have allotted to their use the line and private banks 68 and 69. Said shaft is provided with the cam 70, longitudinal 80 teeth 71, circular teeth 72, normal post arm 73 and coil-spring 74. Said switch is also provided with vertical and rotary line relays 75 and 76 and the vertical and rotary magnets 77 and 78, the release magnet 79, 85 private magnet 80, ringer relay 81, and the vertical and rotary back-bridge relays 82 and 83, respectively. The side switch E performs the usual functions through the medium of the side switch wipers 84, 85, 86 90 and 87.

For supplying ringing current the exchange is provided with a ringer generator F, while all other current is provided through the battery B which has its positive terminal preferably grounded at G. In this system the ringing is done automatically and for that purpose the exchange is, furthermore, provided with an interrupter H for controlling the energizing circuit of the 100 ringer relay 81. It will be understood, of course, that the substations A and A', as disclosed in Fig. 2, are identical.

The operation of the system is as follows: It will be assumed that the subscriber 105 at substation A wishes to call the subscriber at A', the number of which latter is 120. When the receiver 2 is removed from the switch-hook 3 the cam arm 5, upon leaving the spring 88 over which it normally engages, permits the latter to leave the spring 89, thus breaking the ringing circuit, and the same operation permits the primary circuit springs 29 and 30 to come into contact. The first digit being 1 the subscriber 110 operates his dial accordingly, and as soon as the dial is drawn down the ground springs 21 and 22 come into contact, establishing a ground connection from the substation ground G¹ to the ground post 23. As the dial returns, therefore, the impulse wheel 24 thrusts the vertical impulse spring 13 against the ground post 23 once, and then the rotary impulse-tooth 26 in a similar manner carries the rotary impulse spring 14 onto the ground post 23 once. The line conductors 27 and 28 are, therefore, each grounded once, and as a result the vertical line relay 50 of the selector C is first energized by a flow of current from the sub- 115 120 125 130

station ground G^1 through the ground springs 21 and 22 to the vertical impulse spring 13, thence to the vertical line conductor 27, side switch wiper 34, contact point 38, vertical line relay 50, bridge-cut-off relay springs 90 and 91 to the battery lead 92 and through battery B to ground G . The vertical line relay 50 then upon operating once presses the line relay springs 93 and 94 in contact, thus energizing the vertical magnet 52 once by a flow of current from ground G^2 through the springs 94 and 93, private springs 95 and 96 to the vertical magnet 52, thence to the battery lead 92 and from battery B to ground G . The vertical magnet 52, therefore, operates to raise the shaft wipers 31, 32 and 33 to the first level, in a well-known manner. This operation having been accomplished, when the rotary line conductor 28 is grounded the rotary line relay 51 is energized, and this in turn operates the private magnet 53, which latter then trips the side switch to second position, establishing an energizing circuit through the rotary magnet 54 for rotating the wipers onto some trunk line. The energizing circuit through the said rotary line relay 51 extends from the substation ground G^1 to the ground post 23, thence to the rotary impulse spring 14, rotary line conductor 28, side switch wiper 35, contact point 39, rotary line relay 51, bridge-cut-off relay springs 97, 90 and 91 to the battery lead 92, thence through battery B to ground G . The said rotary line relay upon pressing the spring 98 onto the spring 94 closes an energizing circuit through the private magnet 53, as already stated, from ground G^2 through the springs 94 and 98 to the said private magnet 53, thence to the battery lead 92 and through battery B to ground G . The private magnet upon operating permits the side switch to pass to second position, at which time the side switch wiper 41 engages the grounded contact point 45, whereby the energizing circuit for the rotary magnet 54 is closed from ground G^2 to the contact point 45, side switch wiper 37, interrupter springs 99, rotary magnet 54 to the battery lead 92, thence through battery B to ground G . The rotary magnet is then energized and the wipers 31, 32 and 33 are carried into engagement with the first trunk. If the said trunk is not busy, as is well known, the armature of the rotary magnet 54 by mechanically operating the armature of the private magnet 53 releases the side switch to third position, but if the said trunk is busy the private magnet energizes at the same time that the private armature is depressed, and at the instant that the private wiper 33 engages the grounded contact, so that the side switch is held in second position and an energizing circuit is maintained through the

rotary magnet 54 until the private wiper 33 is carried onto the terminal of an idle trunk and the energizing circuit for the private magnet destroyed. At the same instant, of course, the side switch passes to third position and the wiper 37 leaves the contact point 45, thus breaking the energizing circuit for the rotary magnet 54 and bringing the selector to a standstill. The passage of the side switch to third position, of course, carries the side switch wipers 34 and 35 onto the contact points 46 and 47, and the line conductors 27 and 28 are placed in connection with the line wipers 31 and 32 which, having already entered into connection with the trunk conductors 100 and 101 that lead to the connector D, place the said conductors 27 and 28 also in connection with the said connector D. The passage of the side switch to third position, furthermore, establishes a guarding potential at the private wiper 33 when the side switch wiper 36 engages the grounded contact point 48. This potential arrives at the said private wiper 33 from the ground G^1 to the contact point 48, through the side switch wiper 36, back-release relay 56 to the private wiper 33, thereby protecting the trunk conductors 100 and 101 against seizure for the time being.

The said guarding potential, furthermore, sends a current through the ringer relay 81 of the connector D from ground G^1 as traced to the private wiper 33, thence over the said trunk conductor 102, back-bridge relay springs 103 and 104 to the ringer relay 81, through the interrupter H to the battery lead 92, and through battery B to ground G . The said ringer relay 81, of course, begins to operate intermittently each time that the interrupter H permits the closure of said circuit, but the operation of the ringer relay 81 just at this time is of no consequence. The line conductors 27 and 28 having thus been extended to the connector D, the succeeding impulses from the substation A are directed to said connector D. The second digit being 2 the subscriber operates his dial accordingly, grounding the vertical line conductor 27 twice and the rotary line conductor 28 once, as already explained. Each time that the vertical line conductor is grounded the vertical line relay 75 of the connector D is energized by a flow of current from the substation ground G^1 to the vertical line conductor 27, thence through the selector side switch wiper 34 to the contact point 46, vertical line wiper 31, vertical trunk conductor 100 to the vertical line relay 75, thence through said relay and through the vertical back-bridge relay springs 105 and 106 to the battery lead 92, and from battery B to ground G . The vertical line relay 75, each time that it attracts its armature, forces the line relay 125 130 135 140 145 150 155 160 165 170 175 180 185 190 195 200 205 210 215 220 225 230 235 240 245 250 255 springs 107 and 108 into contact, each time sending an impulse through the vertical magnet 77 from ground G^5 through the said springs 108 and 107, conductor 109 (see Fig. 1), private springs 110 and 111, conductor 112, side switch wiper 84, contact point 113' to the vertical magnet 77, thence to battery lead 92, and through battery B to ground G. The vertical magnet, as disclosed in the aforesaid patent, when energized operates to raise the switch-shaft and wipers. The vertical magnet 77 being energized twice the wipers 65, 66 and 67 are raised to the second level. The ground impulse to the rotary line conductor 28, after the switch-shaft 64 has thus been raised, energizes the rotary line relay 76 of the connector, which in turn operates to energize the private magnet 80. The circuit over which the said rotary line relay 76 is energized extends from the substation ground G^1 to the rotary line conductor 28, thence to the side switch wiper 33 of the selector C, contact point 47, rotary line wiper 32, rotary trunk conductor 101 to the said rotary line relay 76, thence to battery lead 92 and through battery B to ground G. The rotary line relay 76 upon attracting its armature forces the spring 113 onto the spring 108, whereby a flow of current is sent through the private magnet 80 from ground G^5 , through the springs 108 and 113, conductor 114 to the private magnet 80, thence through conductor 115, vertical back-bridge relay springs 105 and 106 to the battery lead 92, thence through battery B to ground G. The private magnet 80 upon attracting its armature and then de-energizing operates, of course, to release the side switch E from first to second position. The effect of the shifting of the side switch is to substitute the rotary magnet 78 for the vertical magnet 77, bringing the former under the control of the vertical line relay 75 when the side switch wiper 84 leaves the contact point 113' and engages the contact point 116. The third digit being 0, when the vertical line conductor 27 is grounded ten times by the subscriber upon operating the dial corresponding to the said digit 0, the vertical line relay 75 is energized ten times over circuits that are described, which relay in turn causes the step-by-step energization of the rotary magnet 78. The energizing circuit through said rotary magnet extends from ground G^5 through the line relay springs 108 and 107, conductor 109, private springs 110 and 111, conductor 112, side switch wiper 84, contact point 116 to the rotary magnet 78, thence through battery lead 92 and through battery B to ground G. The rotary magnet 78 being energized ten times the shaft 64 is rotated ten steps, in the well-known manner, whereby the wipers 65, 66 and 67 are car-

ried into engagement with the tenth terminal of the second level, from which terminal lead the normal conductors 117, 118 and 119 that extend to the selector C' of the called line; the former two of which conductors continue through to the called substation #120. After the connector has thus been operated the ground impulse to the rotary line conductor 28 energizes the rotary line relay 76 of the connector over circuits that are already well known, which relay in turn operates the private magnet 80, as before. The said private magnet upon energizing will, if the line is busy, close a circuit through the release magnet 79 to release the switch; but it will be assumed for the present that the line is not busy and that the side switch E passes to third position when the private magnet 80 deenergizes.

As soon as the side switch passes to third position a guarding potential is established at the private wiper 67, when the side switch wiper 85 engages the grounded contact point 120. This guarding potential prevents any other subscriber from calling-in on the line #120 for the time being. This guarding potential, furthermore, sends a flow of current through the bridge-cut-off relay 121 of the selector C'. This circuit extends as traced to the private wiper 67 to the private normal 119, thence through the switch-shaft springs 122 and 123 to the bridge-cut-off relay 121, thence to the battery lead 92 and through battery B to ground G. The said relay 121 upon energizing separates the springs 124, 125 and 126, disconnecting the line relays 127 and 128 from the battery lead 92, and from each other. As soon as the side switch wipers 86 and 87 pass into engagement with the contact points 129 and 130, the ringer relay springs 131 and 132 are extended to the line wipers 65 and 66 and, therefore, each time that the ringer relay 81 energizes ringing current is sent out to the called subscriber's station from the ringer generator F through the ringer relay springs 133 and 134 to the side switch wipers 86 and 87, line wipers 65 and 66, normal conductors 117 and 118 to the line conductors 135 and 136 and through the ringer 137. When the subscriber at substation #120 answers, the primary circuit springs 138 and 139 then close in contact, establishing a circuit through the transmitter 140, primary winding 141, in series with the back-bridge relays 82 and 83 of the connector, and the said relays 82 and 83 therefore energize simultaneously. It will be noticed that the resistance-coil 142 at the connector D is bridged across the conductors 143 and 144, but the resistance of said coil is so high that the relays 82 and 83 do not receive enough current to operatively energize them at the instant that the side switch passes to third

position. When the subscriber answers, however, and since the resistance through the transmitter 140 is much lower, the current that passes through the said circuit is sufficient to operate the relays 82 and 83. The springs 105, 106 and 144' controlled by the back-bridge relay 82 are so adjusted that the spring 105 leaves the spring 106 and engages the spring 144' before the spring 104 engages the spring 145. The object of this arrangement is to energize the line relays 75 and 76 before the springs 104 and 145 come into contact. As soon as the spring 105 engages the spring 144' an energizing circuit is established through the line relays 75 and 76 in series, and current flows from ground G^1 to the back-bridge relay springs 144' and 105, thence through the vertical line relay 75, vertical trunk conductor 100, through the transmitter 7 and primary winding 9 of the substation A back to the rotary trunk conductor 101, thence through the rotary line relay 76 to the battery lead 92 and through battery B to ground G . As soon as the relays 75 and 76 energize the springs 146 and 147 separate, while the springs 147 and 148 engage in contact. The separation of the springs 146 and 147 occurs before the back-bridge relay springs 104 and 145 come into contact, and the called subscriber, therefore, controls the supply of talking current to the calling substation. As soon as the front and back bridge relays 75, 76, 82 and 83 energize, the springs 103 and 104 separate, and also the springs 146 and 147; therefore, the energizing circuit for the ringer relay 81 is destroyed and the ringer relay springs 131 and 149, and also the springs 132 and 150, remain in contact. The subscribers being thus provided with talking current are able to converse with each other over the circuit that is indicated by the heavy conductors in Fig. 2, which circuit passes through the condensers 151 and 152 that divide the talking circuit into two sections, which sections provide the connected subscribers with talking current. It will be seen that the private magnet is short-circuited while the subscribers are talking, and the object in thus short-circuiting the private magnet is to prevent it from energizing. After the subscribers are through talking the calling subscriber may release the switches by restoring the receiver 2 and thus causing the switch-hook 3, through the medium of the arm 6, to press the release-springs 15, 16 and 17 into contact. The vertical and rotary line conductors 27 and 28 are thus grounded simultaneously from the substation ground G^1 to the ground release spring 17, from whence the current divides to the springs 16 and 15, passing to the rotary and vertical line conductors 28 and 27. Since the inside terminal of the vertical side of the line is grounded at G^1 , as already explained, the grounding of the said line at the substation short-circuits the vertical line relay 75 and, of course, the said relay de-energizes. Upon de-energizing the springs 146 and 147 come into contact while the back-bridge relay springs 104 and 145 remain in contact. Therefore a circuit is established through the release magnet 79 of the connector, in series with the back-release relay 56 of the selector C, from ground G^1 at the selector side-switch to the contact point 48, through the wiper 36, back-release relay 56 to the private wiper 33, trunk release conductor 102, vertical line relay springs 146 and 147, through the back-bridge relay springs 104 and 145 to the release magnet 79, thence to the battery lead 92 and through battery B to ground G . The release magnet 79 upon attracting its armature releases the switch-shaft 64 and the side-switch E in the well-known manner, thus breaking the energizing circuit through the back-bridge relays 82 and 83, when the side switch wiper 85 leaves the grounded contact point 120. As soon as the said back-bridge relays de-energize the springs 104 and 145 separate and the release magnet 79 de-energizes, restoring the switch to normal condition and restoring the springs 104 and 103, and 106 and 105 into normal contact. In the mean time the back-release relay 56 of the selector, by pressing the back-release relay springs 153 and 154 into contact, energizes the release magnet 55, which latter attracts its armature and remains in readiness to release its switch as soon as the release magnet 55 de-energizes. The de-energization of said release magnet occurs when the back-release relay 56 de-energizes at the moment that the back-bridge relay springs 104 and 145 of the connector D separate. If the called subscriber instead of the calling subscriber hangs up his receiver first, since the resistance-coil 142 is bridged across the conductors 143 and 144 (Fig. 1) as previously explained, the back-bridge relays 82 and 83 do not de-energize, because the current that passes through the resistance-coil 142 is sufficient to retain the relays 82 and 83 in an operative condition. Therefore, the said resistance-coil 142 is provided to prevent the called subscriber from taking any part in the release. If the calling subscriber wishes to release when the connector side switch is in first or second position, or in third position,—before the called subscriber has answered and, therefore, before the relays 82 and 83 are energized—he does so by grounding the vertical and rotary line conductors 27 and 28 and thereby energizing the vertical and rotary line relays 75 and 76 simultaneously over circuits that have already been pointed out. Therefore, the springs 147 and 148 are brought into contact while

the springs 104 and 103 of the back-bridge are together, and consequently a release will result by a flow of current from the selector ground G⁴ through the back-release relay 56 and trunk release conductor 102, back-bridge relay springs 103 and 104 and front-bridge relay springs 147 and 148 to the release magnet 79 and through said magnet to battery B. It will be noticed that talking current is supplied to the called subscriber's line from battery B and through the back-bridge relays 82 and 83 direct, and in a similar manner current is supplied to the calling subscriber through the line relays 75 and 76 direct from battery B. By substituting the connector D' (Fig. 3) for the connector D (Fig. 2) the system is then similar to the one described in the preceding. Since all parts contained in the connector D' are identical with those contained in the connector D, they are given like numerals. By the use of this modified connector the called subscriber may also release the connection to his line by simply hanging up his receiver. In this case, as soon as the receiver breaks the circuit by separating the springs 138 and 139 the relays 82 and 83 deenergize, pressing the springs 103 and 104 into contact before the springs 105 and 144' separate, or at about the same time, in which case a release circuit is established through the release magnet 79 and the back-release relay 56 of the selector C before the line relay springs 147 and 148 separate. This circuit extends, as before, from ground G⁴ at the selector side switch through the back-release relay 56, trunk release conductor 102, through the back-bridge relay springs 103 and 104, line relay springs 147 and 148 to the release magnet 79, thence to the battery lead 92 and through battery B to ground G. As soon as the release magnet 79 energizes the connector is, of course, released as before, and as soon as the line relay springs 147 and 148 separate, because of the separation of the back-bridge relay springs 105 and 144', the release circuit is destroyed, which causes a deenergization of the back-release relay 56, which in turn produces a release of the selector C, as already pointed out. It is evident, therefore, that after the subscribers are through talking, the deenergization of the front-bridge relays 75 and 76, or the deenergization of the back-bridge relays 82 and 83, by the calling or called subscribers, will produce a restoration of the switches. In other words, if at any time the back-bridge relay springs 103 and 104 come into contact while the front-bridge relay springs 147 and 148 are in contact, a release will follow; or if the front-bridge relay springs 146 and 147 come into contact while the back-bridge relay springs 104 and 145 are in contact, a release will follow also.

As is well known, busy lines are protected by guarding potentials, and if the called line happens to be busy when the private magnet 80 is energized for the last time, as already explained, the connector-switch D will be released at the instant that the private magnet springs 155 and 156 are brought into contact, since the private wiper 67 is then in engagement with the grounded contact. The release circuit extends from the grounded contact to the private wiper 67, thence to the side switch wiper 85, contact point 157, private magnet springs 155 and 156, release magnet 79 to the battery lead 92, thence through battery B to ground G. The release magnet 79 upon energizing releases the connector-switch shaft and side switch, as is well known, and, of course, the release circuit is broken as soon as the private wiper 67 leaves the grounded contact point. The subscriber at the calling substation then receives a busy signaling current from the busy machine I to the conductor 158, connector side switch contact point 159, side switch wiper 85, rotary back-bridge relay 83, condenser 152, rotary trunk conductor 101, through the primary winding 9 at the substation A and back to the vertical line conductor 27, thence through the vertical line relay 75 at the connector D to the battery lead 92 and back to the busy machine I. The subscriber will then hang up his receiver, grounding both line conductors 27 and 28 and energizing the line relays 75 and 76 of the connector simultaneously, thus bringing the springs 147 and 148 into contact while the back-bridge relay springs 103 and 104 are in contact, producing a release of the switches, as already explained. It will be understood that where a system is to be installed in which ten thousand subscribers must be accommodated another selector-switch must be inserted between the selector C and connector D, and the trunk conductor similar to the trunk conductor 102 leading from the private wiper 33 would then lead to a back-release relay spring similar to the back-release relay spring 153, and the said spring 153 would not then be connected to ground, as shown in Fig. 2. The back-release relay of the interposed selector would, of course, like the back-release relay 56, be connected with the connector D, as shown in Fig. 2; and then each time that the back-release relay of the said interposed selector energizes, the release magnet similar to the release magnet 55, upon the energization of the relay, would be connected through springs similar to the springs 154 and 153 with the back-release relay 56 of the selector C, and the release would, of course, follow accordingly.

From the foregoing it will be seen that the two front-bridge relays and the two back-bridge relays of the connector D are 130

not only sufficient for feeding current to the lines for talking purposes, but are also sufficient for controlling the connecting and releasing operations of the connector, as well as the releasing of the other switch or switches back toward the calling telephone line. In this way I avoid the use of certain more or less expensive or undesirable devices which have heretofore been considered necessary, such, for example, as the differential relay windings or other additional coils in the front and back bridges of the connectors.

From the preceding it will be evident that the ringer relay 81, which energizes as soon as the side switch of the selector C passes to third position, does so over a circuit which branches at the connector into two sections, one section, as previously described, extending through the back-bridge relay springs 103 and 104 to the ringer relay and thence to the interrupter H to the battery, and the other circuit through the front-bridge relay springs 146 and 147 to the said ringer relay. In order to destroy the ringer relay circuit, therefore, it is necessary that the vertical front and back bridge relays 75 and 82 be energized at the same time.

It has been explained that when the called subscriber answers, the front-bridge relays 75 and 76 energize owing to the engagement of the back-bridge relay springs 105 and 144', and that the springs 146 and 147 of the front-bridge are separated before the springs 104 and 145 of the back-bridge engage. This may not be an exact statement of the operation, but at any rate the energization of the front-bridge relays 75 and 76 occurs sufficiently soon after the back-bridge relay springs 105 and 144' engage to prevent a release from occurring by the engagement of the back-bridge relay springs 104 and 145.

It will be noticed that the release, when the calling subscriber hangs up his receiver before the called subscriber, is dependent upon the deenergization of the vertical line relay 75, and more particularly upon the engagement of the front-bridge relay springs 146 and 147. Therefore, whatever operation at the substation will cause the deenergization of the said relay 75 during a time that the back-bridge relay springs 104 and 145 are kept in contact will produce a release. It will be evident, therefore, that the grounding of the line conductors 27 and 28 is not absolutely necessary at this stage to produce a release, as the simple opening up of the subscriber's line conductors 27 and 28 will produce the same result, namely the deenergization of the vertical line relay 75, which will, of course, as explained, produce the release. The opening up of the subscriber's line circuit, it has been explained, occurs when the cam arm 5 at the substation A engages the ringer circuit

spring 88, at which time the primary circuit springs 29 and 30 separate, leaving the subscriber's line conductors normally open. This in itself is sufficient to restore the switching apparatus at the central office. It therefore follows that either the grounding of both sides of the calling line or the opening up of the line will produce a release.

In this system the resistances of the various coils may be varied considerably, but I find that good results are obtained when the back-release relay 56 of the selector C is wound to a resistance of about one-half ohm, while the release magnet 79 of the connector D is wound to a resistance of about sixty ohms, the ampere turns in both of these coils being sufficient to permit them to energize in series with a battery B of about fifty volts. The ringer relay 81 may be of about three hundred and fifty to five hundred ohms, if desired, so that it may energize in series with the winding of the back-release relay 56 of the selector C, but cutting down at the same time the amperage in the circuit so that the ampere turns of the back-release relay 56 will not be sufficient to cause the energization of the said back-release relay 56. The front-bridge relays 75 and 76, or the vertical and rotary line relays as they are called, may be wound to a resistance of five hundred ohms each, although a considerable variation may be made. The back-bridge relays 82 and 83 may be wound to a resistance of about three hundred and fifty ohms each, while the resistance-coil 142 may be one thousand ohms. The vertical, rotary and private magnets of the connector may be the same as those of the patent referred to.

What I claim as my invention is:—

1. A telephone connector-switch provided with parallel voice-current conductors, a condenser in each conductor, a front-bridge provided with a pair of line relays, a back-bridge provided with a pair of relays, a battery included in both bridges, step-by-step mechanism controlled by at least one of said relays, and release mechanism controlled by at least one of said relays, said relays constituting the sole or only artificial resistance between the battery and the said talking conductors.

2. A telephone connector comprising a pair of voice-current conductors, an inductive connection in each conductor, a bridge in front of said inductive connections, a bridge back of said inductive connections, electrically-propelled and step-by-step-actuated connecting mechanism, electrically operated release mechanism, a battery included in both bridges, and four electro-magnets included in said bridges, the windings of said electro-magnets constituting the sole or only artificial resistance between

the battery and the voice-current conductors.

3. In a telephone exchange system, the combination of a talking circuit, inductive connections in said circuit, a bridge in front of said inductive connections, a bridge back of said inductive connections, two relays in each bridge, a battery included in both bridges, switching mechanism controlled by at least one of said relays, release mechanism controlled by at least one of said relays, subscribers' telephones receiving talking current from said battery, and subscriber-operated means for controlling the energizing of at least one of said relays, the windings of said relays constituting the sole or only artificial resistance between the battery and the said talking circuit.

4. In a telephone exchange system, the combination of a talking circuit, an inductive connection in each side of the talking circuit, a bridge in front of said inductive connections, a bridge back of said inductive connections, a pair of relays in each bridge, suitable means for supplying talking current through the windings of said relays to the talking circuit, subscribers' telephones receiving the talking current supplied through the said relay windings, switching mechanism controlled by at least one of said relays, release mechanism controlled by at least one of said relays, and subscriber-operated means for controlling the energizing of at least one of said relays, the said relay windings constituting the sole or only artificial resistance through which talking current is supplied to the talking circuit.

5. A telephone connector provided with a pair of voice-current conductors, an inductive connection in each conductor, a bridge in front of said inductive connections, a bridge back of said inductive connections, a pair of relays in each bridge, suitable means for supplying current through the windings of said relays to the said voice-current conductors, switching mechanism controlled by at least one of said relays, and release mechanism controlled by at least one of said relays, the windings of said relays constituting the sole or only artificial resistance through which current is supplied to the said voice-current conductors.

6. In a telephone exchange system, the combination of a calling telephone line, a called telephone line, a selector intermediate the two lines, a connector intermediate the selector and the called line, subscribers' telephones, subscriber-operated means for controlling the selector and connector, and means for supplying talking current through the connector to the calling and called telephone lines, said connector provided with four relay coils constituting the

sole or only artificial resistance through which talking current is supplied to the telephone lines.

7. A telephone connector-switch provided with parallel voice-current conductors, a condenser in each conductor, a front-bridge provided with a pair of line relays, a back-bridge provided with a pair of relays, a battery included in both bridges, step-by-step mechanism controlled by at least one of said relays, release mechanism controlled by at least one of said relays, said relays constituting the sole or only artificial resistance between the battery and the said talking conductors, and a ringer relay controlled by at least one of said bridged relays.

8. A telephone connector comprising a pair of voice-current conductors, an inductive connection in each conductor, a bridge in front of said inductive connections, a bridge back of said inductive connections, electrically-propelled and step-by-step-actuated connecting mechanism, electrically operated release mechanism, a battery included in both bridges, four electro-magnets included in said bridges, the windings of said electro-magnets constituting the sole or only artificial resistance between the battery and the voice-current conductors, and a ringer relay controlled by at least one of said bridged relays.

9. In a telephone exchange system, the combination of a talking circuit, inductive connections in said circuit, a bridge in front of said inductive connections, a bridge back of said inductive connections, two relays in each bridge, a battery included in both bridges, switching mechanism controlled by at least one of said relays, release mechanism controlled by at least one of said relays, subscribers' telephones receiving talking current from said battery, subscriber-operated means for controlling the energizing of at least one of said relays, the windings of said relays constituting the sole or only artificial resistance between the battery and the said talking circuit, and a ringer relay controlled by at least one of said bridged relays.

10. In a telephone exchange system, the combination of a talking circuit, an inductive connection in each side of the talking circuit, a bridge in front of said inductive connections, a bridge back of said inductive connections, a pair of relays in each bridge, suitable means for supplying talking current through the windings of said relays to the talking circuit, subscribers' telephones receiving the talking current supplied through the said relay windings, switching mechanism controlled by at least one of said relays, release mechanism controlled by at least one of said relays, subscriber-operated means for controlling the energizing of at least one of said relays.

least one of said relays, the said relay windings constituting the sole or only artificial resistance through which talking current is supplied to the talking circuit, and a ringer relay controlled by at least one of said bridged relays.

11. A telephone connector provided with a pair of voice-current conductors, an inductive connection in each conductor, a bridge in front of said inductive connections, a bridge back of said inductive connections, a pair of relays in each bridge, suitable means for supplying current through the windings of said relays to the said voice-current conductors, switching mechanism controlled by at least one of said relays, release mechanism controlled by at least one of said relays, the windings of said relays constituting the sole or only artificial resistance through which current is supplied to the said voice-current conductors, and a ringer relay controlled by at least one of said bridged relays.

12. In a telephone exchange system, the combination of a calling telephone line, a called telephone line, a selector intermediate the two lines, a connector intermediate the selector and the called line, subscribers' telephones, subscriber-operated means for controlling the selector and connector, means for supplying talking current through the connector to the calling and called telephone lines, said connector provided with four relay coils constituting the sole or only artificial resistance through which talking current is supplied to the telephone lines, and a ringer relay controlled by at least one of said bridged relays.

13. A telephone connector-switch provided with parallel voice-current conductors, a condenser in each conductor, a front-bridge provided with a pair of line relays, a back-bridge provided with a pair of relays, a battery included in both bridges, step-by-step mechanism controlled by at least one of said relays, release mechanism controlled by at least one of said relays, said relays constituting the sole or only artificial resistance between the battery and the said talking conductors, and means for connecting all of said relays with the same pole of the battery when the connector is released.

14. A telephone connector comprising a pair of voice-current conductors, an inductive connection in each conductor, a bridge in front of said inductive connections, a bridge back of said inductive connections, electrically-propelled and step-by-step-actuated connecting mechanism, electrically operated release mechanism, a battery included in both bridges, four electro-magnets included in said bridges, the windings of said electro-magnets constituting the sole or only artificial resistance between the battery and the voice-current conductors, and means for

connecting all of said relays with the same pole of the battery when the connector is released.

15. In a telephone exchange system, the combination of a talking circuit, inductive connections in said circuit, a bridge in front of said inductive connections, a bridge back of said inductive connections, two relays in each bridge, a battery included in both bridges, connector switching mechanism controlled by at least one of said relays, release mechanism controlled by at least one of said relays, subscribers' telephones receiving talking current from said battery, subscriber-operated means for controlling the energizing of at least one of said relays, the windings of said relays constituting the sole or only artificial resistance between the battery and the said talking circuit, and means for connecting all of said relays with the same pole of the battery when the connector is released.

16. In a telephone exchange system, the combination of a talking circuit, an inductive connection in each side of the talking circuit, a bridge in front of said inductive connections, a bridge back of said inductive connections, a pair of relays in each bridge, suitable means for supplying talking current through the windings of said relays to the talking circuit, subscribers' telephones receiving the talking current supplied through the said relay windings, connector switching mechanism controlled by at least one of said relays, release mechanism controlled by at least one of said relays, subscriber-operated means for controlling the energizing of at least one of said relays, the said relay windings constituting the sole or only artificial resistance through which talking current is supplied to the talking circuit, and means for connecting all of said relays with the same pole of said means for supplying talking current when the connector is released.

17. A telephone connector provided with a pair of voice-current conductors, an inductive connection in each conductor, a bridge in front of said inductive connections, a bridge back of said inductive connections, a pair of relays in each bridge, suitable means for supplying current through the windings of said relays to the said voice-current conductors, switching mechanism controlled by at least one of said relays, release mechanism controlled by at least one of said relays, the windings of said relays constituting the sole or only artificial resistance through which current is supplied to the said voice-current conductors, and means for connecting all of said relays with the same pole of said means for supplying current when the connector is released.

18. In a telephone exchange system, the combination of a calling telephone line, a

- called telephone line, a selector intermediate the two lines, a connector intermediate the selector and the called line, subscribers' telephones, subscriber-operated means for controlling the selector and connector, means for supplying talking current through the connector to the calling and called telephone lines, said connector provided with four relay coils constituting the sole or only artificial resistance through which talking current is supplied to the telephone lines, and means for connecting all of said relays with the same pole of said means for supplying talking current when the connector is released.
19. An automatic telephone connector provided with a release circuit having two parallel and normally open branches, parallel voice-current conductors, inductive connections in said voice-current conductors, a relay bridge in front of said inductive connections, a relay bridge back of said inductive connections, a set of switch springs for each relay bridge, the continuity of each said parallel branch being controlled by relay springs of both bridges.
20. A telephone connector provided with a release circuit having normally open parallel branches, a pair of relays, another pair of relays, a set of switch springs for each pair of relays, the continuity of each said parallel branch being controlled by springs of both pairs of relays.
21. A telephone exchange connector provided with a release circuit having normally open parallel branches, a talking circuit, a relay bridge across said circuit, another relay bridge across said circuit, a set of switch springs for each bridge, circuit connections by which one of said parallel branches is closed by the energizing of one relay bridge when the other bridge is deenergized, and suitable circuit connections by which the other parallel branch is closed by the deenergizing of the one relay bridge when the other bridge is energized.
22. An automatic telephone exchange connector provided with a release circuit having normally open parallel branches, one pair of relays, another pair of relays, a normally open and a normally closed switch point in each said parallel branch, the one pair of relays controlling the normally open switch point in one bridge, the other pair of relays controlling the normally open switch point in the other bridge, one relay of the one pair controlling the normally closed switch point in the parallel branch having its normally open switch point controlled by the other pair of relays, and a relay of said other pair controlling the normally closed switch point in the parallel branch having its normally open switch point controlled by the one pair.
23. An automatic telephone exchange connector provided with step-by-step switching mechanism, release mechanism, a release circuit having normally open parallel branches, parallel voice-current conductors, a condenser in each voice-current conductor, a relay bridge in front of said condensers, a relay bridge back of said condensers, a set of switch springs for each relay bridge, one spring of each set being grounded, each said parallel branch having a normally closed switch point controlled by the springs in one set, and a normally open switch point controlled by the springs in the other set.
24. An automatic telephone connector provided with a release circuit having two parallel and normally open branches, parallel voice-current conductors, inductive connections in said voice-current conductors, a relay bridge in front of said inductive connections, a relay bridge back of said inductive connections, a set of switch springs for each relay bridge, the continuity of each said parallel branch being controlled by relay springs of both bridges, and means for furnishing talking current through the relay windings.
25. A telephone connector provided with a release circuit having normally open parallel branches, a pair of relays, another pair of relays, a set of switch springs for each pair of relays, the continuity of each said parallel branch being controlled by springs of both pairs of relays, and means for furnishing talking current through the relay windings.
26. A telephone exchange connector provided with a release circuit having normally open parallel branches, a talking circuit, a relay bridge across said circuit, another relay bridge across said circuit, a set of switch springs for each bridge, circuit connections by which one of said parallel branches is closed by the energizing of one relay bridge when the other bridge is deenergized, suitable circuit connections by which the other parallel branch is closed by the deenergizing of the one relay bridge when the other bridge is energized, and means for furnishing talking current through the relay windings.
27. An automatic telephone exchange connector provided with a release circuit having normally open parallel branches, one pair of relays, another pair of relays, a normally open and a normally closed switch point in each said parallel branch, the one pair of relays controlling the normally open switch point in one bridge, the other pair of relays controlling the normally open switch point in the other bridge, one relay of the one pair controlling the normally closed switch point in the parallel branch having its normally open switch point controlled by the other pair of relays, and a relay of said other pair controlling the normally closed switch point in the parallel branch having its normally open switch point controlled by the one pair.

of said other pair controlling the normally closed switch point in the parallel branch having its normally open switch point controlled by the one pair, and means for furnishing talking current through the relay windings.

28. An automatic telephone exchange connector provided with step by-step switching mechanism, release mechanism, a release circuit having normally open parallel branches, parallel voice-current conductors, a condenser in each voice-current conductor, a relay bridge in front of said condensers, a relay bridge back of said condensers, a set of switch springs for each relay bridge, one spring of each set being grounded, each said parallel branch having a normally closed switch point controlled by the springs in one set, a normally open switch point controlled by the springs in the other set, and means for furnishing talking current through the relay windings.

29. In a telephone exchange system, the combination of a selector provided with a back-release relay, a connector provided with a ringer relay, a trunk line having a third conductor, and an energizing circuit for said ringer relay, said circuit including the third trunk line conductor and a winding of the back-release relay.

30. In a telephone exchange system, the combination of a selector provided with a back-release relay, a connector provided with a ringer relay, a trunk line, and an energizing circuit for said ringer relay, said circuit including a trunk line conductor and a winding of said back-release relay.

31. In a telephone exchange system, the combination of a selector provided with a back-release relay, a connector provided with a ringer relay, and an energizing circuit including the windings of the two relays in series.

32. In a telephone exchange system, the combination of a connector provided with a ringer relay, a trunk line leading to said connector, and an energizing circuit for said ringer relay, said circuit including a conductor of said trunk line.

33. In a telephone exchange system, the combination of a connector provided with a ringer relay, a trunk line leading to said connector, and an energizing circuit for said ringer relay, said circuit including the third conductor of said trunk line.

34. In a telephone exchange system, the combination of a talking circuit, inductive connections in said circuit, a front relay bridge, a back relay bridge, and a high resistance bridged across the circuit to maintain a slight flow of current through the back-bridge relays, for the purpose set forth.

35. In a telephone exchange system, the combination of a talking circuit, a step-by-

step switching mechanism, release mechanism, a release circuit, a front relay bridge provided with springs controlling the said switching mechanism and release circuit, a side switch operated by a private magnet, a back relay bridge provided with springs controlling the release circuit, a common battery, connections by which the battery is switched into the front-bridge by the energizing of one of the relays of the back-bridge, connections by which the battery is switched into the back-bridge by the operation of said side switch, said private magnet having an energizing circuit controlled by springs of said relay bridges.

36. In a telephone exchange system, the combination of a talking circuit, step-by-step switching mechanism, release mechanism, a release circuit, a front relay bridge provided with springs controlling the said switching mechanism and release circuit, a side switch operated by a private magnet, a back relay bridge provided with springs controlling the release circuit, a common battery, connections by which the battery is switched into the front-bridge by the energizing of one of the relays of the back-bridge, connections by which the battery is switched into the back-bridge by the operation of said side switch, said private magnet having an energizing circuit controlled by springs of said relay bridges, and a ringer relay provided with a circuit controlled by the springs of the back relay bridge.

37. In a telephone exchange system, the combination of a talking circuit, inductive connections in said circuit, a front relay bridge, a back relay bridge, a set of switch springs for each bridge, a private magnet, a side switch operated by the private magnet, an energizing circuit for said private magnet controlled by springs of both bridges, and means for short-circuiting the winding of said private magnet during conversation.

38. In a telephone exchange system, the combination of a talking circuit, an automatic switch having two pairs of relays bridged across said circuit, means for supplying talking current through the relay windings to the talking circuit, subscribers' telephones receiving talking current from the said means of supply, each relay-coil of each bridge being non-inductively related to the other coils.

39. In a telephone exchange system, an automatic connector provided with a private magnet, a side switch operated by the private magnet, and means for temporarily short-circuiting the winding of said private magnet during use of the connector for maintaining communication between two subscribers.

40. In a telephone exchange system, an automatic switching machine provided with

- step-by-step switching mechanism, a private magnet having suitable control of said switching mechanism, and means for temporarily short-circuiting the winding of said 5 private magnet during use of the switching machine for maintaining communication between subscribers.
41. In a telephone exchange system, an automatic connector provided with a private 10 magnet, a side switch operated by the private magnet, and means for temporarily short-circuiting the winding of said private magnet when the side switch has passed to third position.
42. In a telephone exchange system, an automatic connector provided with a private 15 magnet, a side switch operated by the private magnet, and means for temporarily short-circuiting the winding of said private magnet when the side switch has passed out of normal position.
43. In a telephone exchange system, the combination of an automatic connector provided with a private magnet, a side switch 20 operated by the private magnet, a called telephone line, and means for temporarily short-circuiting said private magnet after connection is established with the called telephone line.
44. In a telephone exchange system, the combination of an automatic switching machine provided with step-by-step switching mechanism, a private magnet suitably controlling switch switching mechanism, a 25 called telephone line, means for temporarily short-circuiting the winding of said private magnet while connection is established with

the called telephone line, and suitable means for establishing the connection with the telephone line.

45. In a telephone exchange system, the combination of a calling subscriber's line, a called subscriber's line, automatic switch mechanism for connecting the two lines together, release mechanism, a release circuit, 45 means for closing the release circuit, a centralized source of talking current, means consisting of a single pair of relay-coils for feeding talking current to the calling subscriber's line, means consisting of a single 50 pair of relay-coils for feeding talking current to the called subscriber's line, and means for preventing a closing of the release circuit by the opening of the called subscriber's line.

46. A telephone connector switch provided with voice current conductors, a condenser in each conductor, a front bridge provided with an electromagnetic device, a back bridge provided with a second electromagnetic device, a battery included in both of 60 said bridges, step-by-step mechanism controlled by one of said electromagnetic devices, and release mechanism controlled by one of said electromagnetic devices, said 65 electromagnetic devices constituting the sole or only artificial resistance between the battery and said talking conductors.

Signed by me at Chicago, Cook county, Illinois, this 21st day of September, 1906.

EDWARD D. FALES.
